UNITED STATES PATENT OFFICE.

ERNEST E. HEINTZ, OF DETROIT, MICHIGAN, ASSIGNOR TO TERNSTEDT MANUFACTURING COMPANY, OF DETROIT, MICHIGAN, A CORPORATION OF MICHIGAN.

WINDOW REGULATOR.

Application filed November 5, 1923. Serial No. 672,793.

This invention relates to window regulators. It is the object of the invention to provide an improved saddle for the supporting of the window sash upon the cable. 5 The saddle is adapted to be stopped at the top and bottom of the permissible movement of the window by positive stops.

Another feature of the saddle is that the same is arranged to ride on a flange on the drum when the saddle passes over the drum, thus relieving the cable of the weight of the sash. Furthermore, an anti-rattling spring is provided to prevent any chattering between the metal of the drum and the 15 metal of the saddle as the same passes over the drum.

In the drawings:

Fig. 1 is an inside elevation of a door frame showing the improved regulator in 20 place.

Fig. 2 is a side elevation of the bottom of the regulator.

Fig. 3 is a perspective view of the rocking support for the lower pulley.

25 Fig. 4 is an elevation of the top of the regulator.

Fig. 5 is a section on the line 5—5 of Fig. 4.

30 Fig. 6 is a section on the line 6—6 of Fig. 5.

Fig. 7 is a section on the line 7—7 of Fig. 5.

35 Fig. 8 is a composite view showing in detail and in perspective the parts that go to make up the saddle.

Cable window regulators are not broadly new. A great many of them have been designed, but a large number of them are subject to infirmities due to the wearing of the 40 cables and also the fact that the drive on the cable is not positive.

It is the object of the present invention to provide an improved saddle which will reduce the wear on the cable to a minimum.

45 The general details of the regulator such as the arrangement of the drum *a*, the driving spool *b*, and the run of the cable *c*, are not made the subject of this application, as the same are claimed in a copending application Serial No. 659,449. Let it be enough to here say that the cable winds around the drum, in a helical groove *d*. It winds around the driving spool *b* in a similar way, thence runs over the direction-giving sheave *e*, parallels the spacer bar *f*

and then runs around the pulley wheel *g*, and returns up the opposite side of the spacer bar *f* to the drum in which it is anchored by means of a clip, as described in the application Serial No. 659,449. 60

However, no claim is made in the application referred to respecting the particular construction of the saddle. It is important that the saddle be constructed so that it will not wear the cable so that it will be fairly 65 secured against dropping away when the window sash is assembled onto it, and so that it will not rattle. These are features that are embodied in a measure in the saddle shown in the application Serial No. 659,449, 70 and also in the improved saddle shown and claimed in the present application.

This saddle comprises a major plate *x* and a minor plate *y*. The cable is looped over the rolls *h* after they have been riveted to the major plate *x* and also up through the notches *i* in the bent-over top flange of the major plate. The minor plate *y* is then riveted to the roll studs and consequently locks the cable tightly to the saddle. This is 75 shown well in Fig. 7. The rolls need not rotate; their purpose is simply to give a good rounded surface of ample arc where the cable enters the saddle. This is the point at which relative movement takes place between the cable and the saddle and where if there is an angular surface the cable will 80 soon saw itself in two. The rolls avoid any trouble on this score. 85

The saddle has also riveted to it a window-supporting pin *j* on which engages the 90 slideable and rotatable bushing *k* provided with the annular groove *m*. This annular groove is adapted to receive the sash plate *w* which is provided with an L shaped slot, which 95 permits the assembly of the sash plate over the bushing.

With chain regulators it has been customary to use simply a U-like clip attached to one of the chain links and a pin for supporting the window. A bushing has also 100 been used. The chain link is locked to the sprocket wheel in climbing over the sprocket and consequently the pin is dependably held in place so that when the sash plate is 105 dropped down over the pin to assemble the sash to the chain no difficulty is found in the way of the pin twisting away from the sash plate. However, with a cable, the pin will turn and twist, consequently it 110

- would be very difficult to assemble the sash plate onto the regulator as is necessary on the job. The custom is to first attach the regulator to the lock board and foot board and then the windows are often put in after the job has been trimmed and painted. It is necessary then to drop them down through the top slot of the window well, and there must be some reliable way of finding and holding the pin so as to slip the sash plate in place. The saddle that I have designed accomplishes this purpose, as the major plate drops clear down over the side of the drum as shown in Fig. 5, while the rolls ride over the top of the drum. The flange *n* on the periphery of the drum rides in between the major plate and the rolls. This causes the saddle to ride the flange and not the cable and hence, relieves the cable of the weight of the sash. This is a very important point as it makes the cable of sufficiently long life to be practical. Obviously, the large amount of plate at the side of the drum and the flange *n* will prevent the rolls from twisting off the top of the drum. This serves to anchor the pin from retreating from the sash plate as the sash plate is pushed down into the window well to locate the pin in the sash plate slot, shown in Fig. 4.
- With the saddle having a large portion of the plate abutting directly against the drum, considerable chattering and rattling might take place, but to avoid this I use a bowed spring *o* which is looped over the metal plate between two pairs of struck out lugs *q*. This takes up any looseness and prevents chattering.
- Secured to the top of the regulator plate *r* is a stop pin *s*. This stops the saddle after the pin has slightly passed the vertical center line of the drum. The consequence is that in this position, the regulator is locked from any actuation originating with the sash, as obviously the saddle cannot force the pin and this is the only way the drum can be turned by such actuation after the saddle has passed the vertical center line. When the sash reaches the downward limit of its movement, another stop *t* which is an integral part of the pulley-carrying yoke *u* stops the sash plate.
- What I claim is:
1. In a window regulator, the combination of a drum provided with a flange at its outer end, a cable running over the drum, and a saddle anchored to the cable and arranged to carry the window panel, the said saddle riding only over this one flange and provided with means for keeping it in upright position to relieve the cable from undue abrasion and wear.
  2. In a window regulator, the combination of a draft member, a flanged drum over which the draft member runs, and a flange-riding saddle for the window comprising a plate anchored at its top to the draft member and having a portion that depends over the side of the drum when the saddle runs over the drum, said plate being provided with an outwardly projecting window-supporting pin.
  3. In a window regulator, the combination of a draft member, a flanged drum over which the draft member runs, and a flange-riding saddle for the window comprising a plate anchored at its top to the draft member and having a portion that depends over the side of the drum when the saddle runs over the drum, said plate being provided with an outwardly projecting window-supporting pin.
  4. In a window regulator, the combination of a draft member, a flanged drum over which the draft member winds, and a flange-riding saddle provided with a plate portion that projects over the side of the drum when the saddle runs over the drum, a pin carried by such plate portion, and the top of the saddle being provided with clamping devices for engaging the draft member.
  5. In a window regulator, the combination of a draft member, a drum over which the draft member runs, and a saddle for supporting the window on the draft member, comprising a major plate, a pair of rolls over which the draft member is looped and clamped to the plate, and a window supporting pin carried by the plate.
  6. In a window regulator, the combination of a draft member, a drum over which the draft member runs, and a saddle comprising a major plate provided with a turned-in plural-notched flange at the top, a pair of rolls supported on the plate, the draft member being looped around the rolls and over the intervening web between the notches of the flange, and a window-supporting pin carried by the plate.
  7. In a window regulator, the combination of a cable, a drum about which the cable winds, and a saddle provided with a depending plate portion engaging the side of the drum when the same passes over the drum, and a spring on the plate for engaging the drum to prevent rattling between the two members.
  8. In a window regulator, the combination of a cable, a flanged drum over which the cable runs, and a saddle provided at its top with means for clamping the cable in place and arranged to ride normally only on the flange of the drum in passing over the drum.
  9. In a window regulator, the combination of a cable, a drum over which the cable winds, said drum provided with an annular flange, and a saddle comprising a major plate, a pair of rolls supported on studs riveted to the major plate, a large portion of the major plate protruding be-

low the flange of the drum and engaging the side of the drum to prevent twisting of the saddle on the drum when the saddle passes over the drum, a window-supporting pin carried on the plate, and a bowed spring carried by the plate for engaging the side of the drum.

10. In a window regulator, the combination of a cable, a flanged drum over which the cable runs, and a saddle provided with a major plate provided with an upper flange having a pair of notches, a pair of rolls provided with studs supported by the major plate, a minor plate clamped to the end of the rolls, the cable being turned over the rolls and looped through the notches in the flange, and a window-supporting pin carried by the major plate.

11. In a window regulator, the combination of a top regulator plate provided with a stop pin, a drum rotatably supported upon the plate, a second rotatable member supported below such plate, a draft member running over the drum and over such second rotatable member, a stop adjacent said second rotatable member, and a window-supporting member or saddle carried on the draft member and stopped in its turning movement on the drum by the stop pin and stopped at the lower end of its movement by the stop located adjacent the second rotatable member.

In testimony whereof he has affixed his signature.

ERNEST E. HEINTZ.
